INTRAVENOUS ROD HOLDER

Joseph P. Saternus, Midlothian, Ill., assignor to Borg-Warner Corporation, Chicago, Ill.

Filed Mar. 24, 1970, Ser. No. 22,195

Term of patent 14 years

Int. Cl. D24—02; D8—03

U.S. Cl. D83—1

FIG. 1 is a perspective view of an intravenous rod holder, showing my new design;

FIG. 2 is a side view of the holder;

FIG. 3 is a top plan view of the holder;

FIG. 4 is a bottom view of the holder.

The broken line portion of FIG. 1 shows an intravenous rod for illustration only.

I claim:

The ornamental design for an intravenous rod holder, as shown and described.
